EMILE GUÉRIN, OF PARIS, FRANCE.

APPARATUS FOR EXAMINING KEENNESS OF VISION AND THE CHROMATIC OR COLOR SENSE.

Application filed September 18, 1923. Serial No. 663,473.

To all whom it may concern:

Be it known that I, EMILE GUÉRIN, citizen of the Republic of France, residing at Paris, France, post-office address 109 Rue du Bac, have invented certain new and useful Improvements in Apparatus for Examining Keenness of Vision and the Chromatic or Color Sense, of which the following is a specification.

- 10 In French Patent No. 544,768, dated the 21 December 1921, a description has been given of a chromo-optometric apparatus, or an apparatus for examining keenness of vision and the chromatic or color sense.
- 15 This apparatus, which is intended to fulfil the various functions of the chromo-optometric disc "Le Mehaute" used in the French Navy, whilst being much less fragile than this latter, much more transportable, 20 more handy and less costly, is constituted in the following manner. It comprises a light box containing a luminous source, the intensity of which can be regulated, such for example as an electric lamp which can 25 be regulated by a rheostat and a photometer giving the indications necessary for the regulation of the lamp to the desired intensity. This box has a frame with rollers upon which is mounted a band of suitable 30 fabric, having the required qualities of transparency and flexibility. The band being wound upon the two rollers which are preferably driven—in order to wind the band in one direction or the other—by a 35 single knob, this band acting as a transparent screen and having a portion bearing the different characters necessary for the examination of the visual sharpness and translucent portions which do not carry 40 any impression and serving for the examination of the chromatic sense by acting like a ground glass screen, which in the Le Mehaute device serves to filter the light which illuminates the colored glasses of the 45 chromatoscope. In front of the roller frame and the band, the box may be provided at will with one or the other of two interchangeable plates, one of which is provided with openings having shutters or the like 50 and serves to enable the examination of the visual sharpness to be carried out by the band, and the other one of which carries a chromatoscope which serves in combination with the blank portion of the band to en-

able the examination of the chromatic 55 sense to be carried out.

This apparatus utilizes either a chromatoscope identical with that of the Le Mehaute, or a chromatoscope especially adapted for use by railways in which the fixed signals, 60 the semaphore combinations and the stop signals for the trains are shown by illumination by transparency of the colored discs appearing through holes of reduced size 65 made by taking into consideration the visibility of the signals and the rule of proportionality in use in the French Navy.

Now the present invention has reference to improvements in the apparatus used for testing visual acuity and the chromatic 70 sense, of the type hereinbefore described. These improvements relate especially to the general organization of the apparatus, the optometric device and the chromatoscope.

The invention primarily consists in arranging the adjustable luminous source at the centre of the light box and in making this latter capable of moving around a vertical spindle or shaft passing through this source, so as to be able to make it turn 80 through an angle of 180 degrees in order to bring opposite the object to be examined either one side of the box or the other according to whether it is desired to examine the visual sharpness or the chromatic sense, 85 the optometric arrangement with its band being, for this purpose, mounted on one of the sides of the apparatus and the chromatoscope on the other. In order therefore to pass from one operation to another, a substitution of the plates is avoided and a simple rotation of the apparatus being all 90 that is necessary.

The invention also consists in utilizing an optometric band having over a certain portion of its length an optotype device of the usual type, with a complete scale of the visual acuities for educated persons and on another portion a similar device, reduced or not, but with special signs provided for illiterate persons, the said band carrying also blank portions forming translucent surfaces which permit of the use of optotypes of a special kind other than those carried by the band, the optometer for this purpose having 100 a hinged door which permits of the reading of such special optotypes. It should be understood that the "optotypes" are the char-

acters, letters, figures or signs, the reading of which determines the degree of visual acuity.

Further according to the present invention a chromatoscope may be employed which is of special utility in navigation and on railways in which the fixed signals, the stop or danger signals in use on railways and the different combinations of semaphores are shown by means of colored discs illuminated by transparent and appearing at holes reduced dimensions taking into account the visibility of the signals and the rule of proportion in use in navigation.

15 The accompanying drawings show, by way of example, the apparatus constructed in accordance with the present invention.

Figure 1 is a longitudinal vertical section.

20 Figure 2 is a horizontal section.

Figure 3 is a front or face view of the roller frame constituting the optometer.

Figures 4 and 5 are front views of the same optometer opened to show the ribbon 25 provided with the usual signs, or lettered or unlettered respectively.

Figure 6 is a face view of the light box, seen from the side, carrying the chromatoscope.

30 The light box 1 of parallelepiped form is mounted upon a pivot formed by the electric lamp 2 round which it can turn and take up two positions at 180 degrees controlled by means of teeth 28 suitably arranged upon 35 the surface of rotation 29.

One of the ends of the light box carries the optometer formed by the roller frame 4 of the known type. The other end carries a chromatoscope 6 suitable for the particular 40 use of the apparatus (marine, railway, aviation, etc.).

This arrangement does away, therefore, at the price of a slight increase in volume, with the use of separate planchettes one substituting itself for the other, according as to 45 whether it was a question of proceeding to examine keenness of vision or that of the chromatic sense. In this way the loss is avoided of one of the essential parts of the 50 apparatus.

The lamp 2 forming a pivot is enclosed in a metal socket 30 provided with a window 31 giving passage to the luminous rays. The socket 30 and the lamp 2 are made in one 55 with the base 29 provided with recesses 32 for ventilation and three feet 33 intended either as shown in Figure 1 to bear upon a general platen 34, on which there are fixed the resistance and a screen 35, or to be placed 60 in the three branches of a foot similar to those used in topography or in photography.

The socket 30 is closed, above the light box 1, by means of a stopper 36 having baffle plates 37 and ventilation holes 38.

65 The electric conductors 36' enter at the

centre of the base 29 in such a manner as not to hamper the rotation of the light box.

The screen 35 arrests the inferior reflections which would entail the risk of incommoding operations.

The whole apparatus is enclosed in a case 39 (Figure 1) and, in order to avoid the necessity of having recourse to a special foot, the apparatus may be fixed by the platen 34 upon the bottom 40 of the case 75 which, in its turn, rests on the four feet 41. The case 39 having been raised and turned up the feet 41 fit into the case which thus becomes a column or pedestal enabling any 80 table to be used for the arrangement of the apparatus on a level with the eyes of a person sitting down.

The optometer, in addition to the windows 10, 10', 10'', which are closed by the shuttered obturators, comprises in the front a 85 hinged door 43 the opening of which releases the ribbon 9 in its whole width which is necessary for the reading of the greatest characters (visual acuity 1/10) of Monoyer's decimal scale.

90 Over a certain length the ribbon has an arrangement of characters—such as shown in Figure 4—with the complete gamut of visual acuities, for educated persons, and on the other part a similar arrangement but reduced to seven series for illiterate persons see Figure 5.

95 White spaces are provided at the ends of the ribbon and between the series of letters such as in Figure 4 and the series of signs such as in Figure 5 for offering, at these three places, after opening the hinged front, translucent surfaces lending themselves to the use of phototypes (Landolt or others) which a practitioner would like to be able 100 to use concurrently with Monoyer's characters or in preference to these latter.

105 Use is made of a known photometer, but provision is made for the use of two or more characteristic photometers of different luminous intensities, so as to be able to realize luminous spaces suitable for special examinations. In Fig. 3 apertures 7 and 8 are shown in the lower part of the member 43, and in Fig. 6 upper apertures 7', 8' are 110 shown at the opposite end of the light box 1.

115 The chromatoscope shown at 6 (Figures 1, 2 and 6) has been especially designed for use in connection with railways. It utilizes the same colored glasses as those already employed for the lines.

120 The device not only enables a practitioner to appreciate the chromatic sense of the subject under examination, but an apparatus for instruction may be made from it quite suitable for teaching the rules or regulations, or to assure oneself of their assimilation.

125 The exposure of the colors employed for the signals has been effected by illuminating by transparency small discs colored respec-

tively red, green, yellow, blue, violet, etc. The holes 44 (Figure 6) through which these small discs appear are of dimensions calculated to bear in mind the visibility of the signals and the rule of proportionality in use in the navy. The hole 44 is doubled by another hole 44' of smaller diameter (1/10 for example of the diameter of 44) corresponding to the limit of visibility.

10 Furthermore it has seemed interesting to make the rear signals of trains appear on the chromatoscope, not only to obtain the differentiation of the red and of the green but also in order to serve for the instruction 15 of the staff.

All the signals have been grouped upon a crown 45 which enables them to defile or pass by so as to render them successively visible through the window 46 (Figure 6) 20 by operating the milled button 47.

It is understood that it is easy to apply a similar arrangement to chromatoscopes which can comply with similar requirements, whether it be a question of railways, 25 aviation, transports companies in common, or for any other motive.

I claim:—

1. Apparatus for testing the visual acuity and chromatic sense comprising, a luminous 30 source consisting of a box movable around an electric lamp serving as a pivot and taking up two positions at 180°, according as to whether it is a question of proceeding to examine the visual acuity or the keenness 35 of the chromatic sense, and an optometric translucent ribbon wound on a system of rollers located at one end of the said box.

2. Apparatus for testing visual acuity and chromatic sense, consisting of a box movable around an electric lamp serving as a pivot for taking up two positions at 180°, according as to whether it is a question of proceeding to examine the visual acuity or that of the chromatic sense, an optometric 45 device located at one of the façades or fronts of the apparatus, an optometric ribbon comprising an arrangement of characters for educated persons, with a complete gamut of the different visual acuities, and a similar 50 arrangement, for illiterate persons, and suitably arranged translucent surfaces permitting of the use of characters of Landolt or others.

3. Apparatus for testing visual acuity and chromatic sense, consisting of a box movable around an electric lamp serving as a pivot for taking up two positions at 180°, according as to whether it is a question of proceeding to examine the visual acuity or that of the chromatic sense, an optometric 55 device located at one of the façades or fronts of the apparatus, an optometric ribbon com-

prising an arrangement of characters for educated persons, with a complete gamut of the different visual acuities, and a similar 65 arrangement for illiterate persons, and suitably arranged translucent surfaces permitting of the use of characters of Landolt or others concurrently with the characters of Monoyer.

4. Apparatus for the examination of visual acuity and of the chromatic sense, consisting of a box movable around an electric lamp serving as a pivot and taking up two positions at 180°, according as to whether 70 it is a question of proceeding to examine the visual acuity or that of the chromatic sense, an optometric device located at one of the façades or fronts of the apparatus, an optometric ribbon comprising an arrangement 75 of characters for educated persons, with a complete gamut of the different visual acuities and a similar arrangement, for illiterate persons, suitably arranged translucent surfaces permitting of the use of characters 80 (Landolt or others) concurrently with the Monoyer characters, and a chromatoscope especially adapted for use by railways in which the fixed signals, the combinations 85 and the rear signals of the trains are shown 90 by illuminating by transparency, colored discs appearing through holes of reduced sizes, due consideration being given to the visibility of the signals and the rule of proportionality in use in the French Navy. 95

5. Apparatus for the examination of visual acuity and of the chromatic sense, consisting of a box movable around an electric lamp serving as a pivot and taking up two positions at 180°, according as to 100 whether it is a question of proceeding to examine the visual acuity or that of the chromatic sense, an optometric device located at one of the façades or fronts of the apparatus, an optometric ribbon comprising an arrangement 105 of characters for educated persons, with a complete gamut of the different visual acuities and a similar arrangement, for illiterate persons, suitably arranged translucent surfaces permitting of the use of suitable characters (Landolt or others), and a chromatoscope especially adapted for use by railways in which the fixed signals, the combinations and the rear 110 signals of the trains are shown by illuminating by transparency, colored discs appearing through holes of reduced sizes, due consideration being given to the visibility of the signals and the rule of the proportionality in use in the French Navy. 115

In testimony whereof I affix my signature.

EMILE GUÉRIN.
